UNITED STATES PATENT OFFICE

HARRY E. NORVIEL, OF ANDERSON, INDIANA, ASSIGNOR TO DELCO-REMY CORPORATION, OF DAYTON, OHIO, A CORPORATION OF DELAWARE

LOCK SWITCH

Original application filed August 21, 1926, Serial No. 130,615. Divided and this application filed April 12, 1927. Serial No. 183,143.

This invention relates to controls and locks therefor, and particularly to apparatus for preventing the unauthorized use or theft of an automobile.

5 This application is a division of my co-pending application Serial No. 130,615, August 21, 1926.

One of the objects of the present invention is to provide a controller which may be 10 unlocked by the use of a key, but movement of the controller to operating position is prevented so long as the key remains in the lock. Preferably, the controller includes means for automatically moving the operating 15 member of the controller to operating position when the key is withdrawn from the lock.

The invention is susceptible of many 20 applications, and, when applied to an electric switch, the objects of the invention are accomplished by providing an electric switch with means such as a spring tending to move the movable contact of the switch to closed 25 position, a key operated device for releasing the spring and a device which permits unlocking the switch but prevents complete movement of the switch to closed position so long as the key is in the lock. Consequently, when the key is removed the switch 30 will be automatically moved by the spring to closed position.

A further object of the invention is to provide a combined switch and lock comprising 35 separate unitary sub-assemblies, one of which includes an operating member and lock therefor and the other of which includes the complete switch. When these sub-assemblies are joined together the operating member of the switch will be positioned for 40 operation by the operating member of the controller.

A further object of the invention is to provide a unitary ignition coil, ignition circuit switch, controller for the switch and 45 lock therefor including novel features such as mentioned in the foregoing paragraphs.

Further objects and advantages of the present invention will be apparent from the following description, reference being had 50 to the accompanying drawing, wherein a

preferred form of embodiment of the present invention is clearly shown.

In the drawing:

Fig. 1 is a front view of a unitary lock and switch constructed in accordance with 55 the present invention, the rectangle drawn with dot and dash lines representing the instrument board to which the structure may be attached.

Fig. 2 is a longitudinal sectional view on 60 the line 2-2 of Fig. 1.

Fig. 3 is a view similar to Fig. 2 showing certain parts in positions differing from the positions shown in Fig. 2.

Fig. 4 is a sectional view on the line 4-4 65 of Fig. 3.

Figs. 5 and 6 are sectional views taken respectively on the lines 5-5 and 6-6 of Fig. 2.

The controller and lock therefor which comprises one of the unitary sub-assemblies 70 of the structure shown in the drawing will first be described.

This controller includes an operating member comprising an endwise movable member 20, and a cupped disc 21 carrying 75 a metal stud 22 surrounded by a non-conducting tube 23. As will appear more clearly hereinafter these parts 20 to 23 constitute the operating member of the controller although the member 20 might be referred to as the operating member, and the parts 22 and 23 collectively as means for transmitting motion from the operating member 20. The members 20 and 21 are 80 slidable within a tubular guide or bearing 24 which together with a tubular outer jacket 25 and a plate 26 provide a case and support for the operating member and lock of the controller. The jacket 25 is provided with an inwardly extending flange 27 which 85 engages a shoulder 28 of the guide 24, and with a plurality of tangs 29 which extend through holes 30 in the plate 26 and are bent over so as to secure the casing members 24, 25 and 26 in assembled relation. A screw 90 pin 31 extends through the members 25 and 24 in order to prevent relative rotation between them. Rotation between members 20 and 24 is prevented by providing the member 20 with an elongated groove 32 which re- 100

ceives the inner end of a screw 33 which is threaded into a tapped hole extending through the side wall of the member 24. A spring 40 tends to move the operating member 20 toward the left or toward operating position as will appear more clearly hereinafter. The operating member 20 is locked in non-operating position shown in Fig. 2 by a bolt 41 which is adapted to enter a recess 42 in a side wall of the member 24. The bolt 41 is slidable within a recess 43 in the member 20 and is urged into locking position by a spring 44. The operating member 20 carries a rotatable key barrel or cylinder 45 which can be turned only by the proper key indicated at 46 in Fig. 3. The mechanism for causing the bolt 41 to be withdrawn from the recess 42 when the key cylinder 45 is rotated has been omitted as illustration thereof will be unnecessary to those skilled in the art. It will be understood, however, that the parts 20, 24, 41, 44 and 45 are comprised in what is known to the trade as the automobile type cylinder lock. It will be understood that when the cylinder 45 is rotated by the key the bolt 41 will be withdrawn from the recess 42 thereby releasing the spring 40 in order to cause the operating member 20 to be moved toward the left, until the right hand end of the groove 32 engages the inner end of the screw 33. After this movement has taken place the key 46 may be released to allow the spring 44 to move the bolt 41 against the interior surface of the casing member 24. Then the key 46 may be withdrawn. The operating member 20 may be moved toward the right into non-operating position and locked in said position without the use of a key. It will be apparent that when the operating member 20 has been moved so that the plunger 41 will be in alignment with the recess 42 the spring 44 will automatically move the plunger 41 in locking position.

In order to compel the operator of the controller to remove the key before the operating member 20 can be moved fully to operating position, means operated by the key 50 are provided for preventing the full movement of the operating member 20 toward the right or into operating position while permitting the bolt 41 to be withdrawn from the recess 42, and while permitting the operating member 20 to be moved a limited amount so that the locking bolt 41 will be held in unlocked position by engagement with the interior wall of the casing member 24. This key controlled device comprises a movable stop 50 which is located within a recess 51 provided in the right end of the operating member 20. The stop 50 is attached to the squared end of the shaft 51 which extends through and is rotatably supported by the operating member 20. The

left end or exposed end of the shaft 51 is also square and is attached to a cover 52 for the key hole 53 of the cylinder 45. The cover 52 is maintained in position covering the key hole 53 as shown in Figs. 1 and 4 and the stop 50 is maintained in position entirely within the periphery of the operating member 20 by a spring 54 having its intermediate portion coiled around the shaft 51, one end bearing against a pin 55 attached to member 20 and the other bearing against a side wall 56 of the cover 52. The spring 54 is biased so as to tend to move the cover 52 in a clockwise direction as viewed in Fig. 4 and the movement of the cover is limited by engagement with the stop 55. When the key 46 is inserted in the key operated member or cylinder 45 the cover 52 will be moved from the full line position shown in Fig. 1 to the position 52a (indicated by dot and dash lines in Fig. 1) and the stop 50 will be moved from the full line position shown in Fig. 5 to the position 50a (indicated by dot and dash lines in Fig. 5). Therefore the inserting of the key 46 in the lock will cause the stop 50 to move into a recess 57 provided by cutting away a portion of the side wall of the casing member 24. The recess 57 is of such width relative to the thickness of the stop 50 as to permit movement of the operating member 20 from the position shown in Fig. 2 to that shown in Fig. 3, the cylinder 45 having been turned by the key 46 to withdraw the bolt 41 from the recess 42. Therefore, so long as the key 46 remains in the key cylinder 45 the operating member cannot move the full amount toward the left into operating position. When the key 46 is withdrawn the spring 54 will be released to return the cover 52 and the stop 50 to normal position as indicated in full lines in the drawing, thereby permitting the spring 40 to complete the movement of the operating member 20 toward the left or until the right hand end of the groove 32 engages the inner end of the screw 33.

While the controller may be used to operate various sorts of mechanisms particularly for rendering some essential part of an automobile operative or inoperative, the form of control which has been illustrated is particularly adapted for controlling an electric switch which may be included alone or with an ignition coil in a unitary sub-assembly which is adapted to be attached to the plate 26 forming a part of the controller and lock sub-assembly.

The sub-assembly including the electric switch for an ignition coil will now be described. The ignition coil comprises a central magnetizable core 60 surrounded by secondary coil 61 and a primary coil 62. These coils are surrounded by an external magnetic circuit 63 and all of these parts are housed within a container which com-

prises a metal tube 64 attached to non-conducting end members 65 and 66. The member 65 carries terminals 67 and 68 connected with the ends of the primary coil 62, respectively. The terminal 68 is connected with the outside end of the secondary winding 61 and its inside end is connected with a terminal 69. One of the turns of the primary winding 62 is cut to provide leads 70 and 71 which extend through hollow rivets 72 and 73, respectively, and are attached to switch contacts 74 and 75, respectively. The rivets 72 and 73 secure said contacts 74 and 75, respectively, to the member 66. Member 66 is provided with a recess 76 for receiving a nonconducting tube 77 having diametrically opposite notches 78 and 79 for receiving, respectively, the inner ends of the switch contacts 74 and 75. The contacts 74 and 75 maintain the tube 77 within the recess 66; and, since the inner ends of these contacts fit somewhat snugly within the notches 78 and 79, rotation of the contacts 74 and 75 with respect to their attaching rivets 72 and 73, respectively, is prevented.

The stationary contacts 74 and 75 are adapted to be engaged by the outwardly extending flange 80 of a metallic, cup-shaped switch operating member 81 which is located within the tube 77. A spring 82 tends to urge the contact operating member 81 outwardly with respect to the recess 76 and its flange 80 into engagement with the contacts 74 and 75. It is therefore apparent that these contacts will maintain the contact actuator 81 within the tube 77.

The non-conducting end member 66 is supported by a metallic coil housing end member 90 which is attached at 91 to the coil housing tube 64 and which is provided with an aperture through which a portion of the non-conducting member 66 extends as shown in Figs. 2 and 6. A case or support for the switch is provided by the members 66 and 90 and by a flanged collar 92 which is permanently secured to the metal core housing tube 64. The collar 92 has an outwardly extending flange 93 which is adapted to be secured to the plate 26 by rivets 94 and rivet studs 95. It is therefore apparent that the parts 66, 90, 92 and 26 will provide a housing for the switch.

Like the controller and lock, the ignition coil and switch may be constructed as a separate sub-assembly. When the controller and lock sub-assembly is united to the switch sub-assembly, the operating member of the controller will operatively engage the switch contact operating member. These sub-assemblies may be readily dis-assembled by shearing off the riveted portions in case repairs or displacements of either sub-assembly are desired.

The studs 95 are provided with tapped

holes 96 for receiving screws 97 by which the structure may be attached to the back of an instrument board 98.

The operation of the controller with respect to the switch will now be described. When the controller is in locked position as shown in Fig. 2, the switch contact flange 80 is separated from the contacts 74 and 75, thereby breaking the circuit of the primary winding of the ignition coil. The flange 80 is spaced from the end wall of the recess 76 so as to permit complete movement of the operating member 20 to locking position while at the same time allowing for variations in manufacture.

When the key 46 is inserted in the cylinder 45 and turned to withdraw the bolt 41 from the recess 42, the operating member 20 will be automatically moved by the spring 40 into the position shown in Fig. 3 where in the locking bolt 41 is held in retracted position. Due to the engagement of the stop 50 with the wall 57a defining the recess 57, movement of the operating member 20 is arrested and hence the contact flange 80 can-

not engage the switch contacts 74 and 75 while the key remains in the lock. This feature compels the car driver to withdraw the key from the lock in order to start the engine of the automobile. When this is done the stop 50 will automatically move away from the recess 57 as already described and the spring 40 will be released to move the operating member 20 further toward the left so that the spring 82 may move the contact flange 80 into engagement with the contacts 74 and 75.

When the operating member 20 has completed its full movement toward the left, and when the contact flange 80 has engaged the contacts 74 and 75 there will be a slight space between the right hand end of the non-conducting tube 23 and the left hand end of the contact actuator 81. In this way the closing of the switch is assured although there may be some slight variations in manufacture.

To open the switch the operator has but to push in the operating member 20 until the bolt 41 is in alignment with the recess 42 whereupon the spring 44 will be released to maintain the operating member in non-operating position and the switch in open position.

One of the principal advantages of the present invention is that the operator is required to remove the key from the lock before the controller can be moved to operating position to render operative some essential part of the automobile such as the ignition apparatus. Another feature is that the controller may be moved and locked in non-operating position or the ignition switch in open position without the use of a key. As a result of these features the likelihood of a car driver leaving the key in the lock

when leaving the car has been substantially eliminated. Another feature of the invention is that the controller is automatically moved to operating position to permit movement of the switch to on position when the key is removed from the lock. No further manipulation by the operator is required to render the ignition apparatus operative.

While the form of embodiment of the present invention as herein disclosed, constitutes a preferred form, it is to be understood that other forms might be adopted, all coming within the scope of the claims which follow.

15 1. What is claimed is as follows:

1. An electric circuit controller and lock therefor comprising, in combination, a unitary sub-assembly including a linearly movable operating member, a lock therefor, and 20 a case for the member and lock; a unitary sub-assembly including a switch having a linearly movable contact and a case for the switch; means for connecting the two cases; and means including in one of the sub-assemblies for transmitting motion from the operating member to the movable contact and extending through an opening in one of the cases.

2. An electric circuit controller and lock 20 therefor comprising, in combination, a unitary sub-assembly including a linearly movable operating member, a lock therefor, a case for the member and lock and having an opening, a motion transmitting member 35 operated by the operating member and extending through said opening; a unitary sub-assembly including a switch having a linearly movable contact operating member and a case for the switch; and means for connecting the two cases, said case being adapted, when connected to locate the movable contact operating member in the path of movement of the motion transmitting member.

45 3. An electric circuit controller and lock therefor comprising, in combination, a unitary sub-assembly including a linearly movable operating member, a lock therefor, a case for the member and lock and having an opening, a motion transmitting member operated by the operating member, and located in alignment with said opening; a unitary sub-assembly including a switch having a linearly movable contact operating member, 50 and a case for the switch; and means for connecting the two cases so that the motion transmitting member will be in alignment with the contact operating member, one of said members extending through said 55 opening in the first mentioned case.

60 4. An electric circuit controller and lock therefor comprising, in combination, a unitary sub-assembly including a linearly movable operating member, a lock therefor, and 65 a support for the member and lock; a uni-

tary sub-assembly including a switch having a linearly movable contact operating member and a support for the switch; and means for connecting the supports, said sub-assemblies being adapted when connected to operatively connect the two operating members.

5. An electric circuit controller and lock therefor comprising, in combination, a unitary sub-assembly including an operating member, a lock therefor, and a support for slidably supporting the operating member for linear movement and for supporting the lock; a unitary sub-assembly including a switch, a supporting base providing a recess, a linearly movable contact actuator having a conducting flange movable within the recess, a spring within the recess urging the contact outwardly relative to the recess, stationary contacts insulatingly supported by the base and projecting into alignment with the recess and engageable with the contact flange to close the switch and to limit movement of the contact actuator by said spring; and means for connecting the lock support and switch base and for locating the contact actuator in alignment with said operating member so as to be operated thereby.

6. An electric circuit controller and lock therefor, comprising in combination, a first unitary sub-assembly including a frame, an operating member for movement along the frame, means for arresting the movement of the member along the frame at successive steps throughout its limit of movement, a second unitary sub-assembly including relatively fixed contact terminals, a movable contactor, means for supporting the contact terminals and the movable contactor for separable engagement, a case securing the supporting means and enclosing the terminals, and means for joining the frame of the first sub-assembly to the case of the second sub-assembly so that the movable member will be adapted to actuate the movable contactor and arrest it in successive steps as the said member is arrested in its movement within the frame.

7. An electric circuit controller and lock therefor, comprising in combination, a casing, switch terminals provided within the casing, a contactor normally urged to engage and bridge said terminals, an actuator assembly for mounting upon said casing and including a linearly movable member and means for connecting it in its movement through an aperture in the first said casing with the said contactor, said member being 120 slidable in the second said casing, and means for arresting its movement therealong in a plurality of positions.

In testimony whereof I hereto affix my signature.

HARRY E. NORVIEL. 130
